UNITED STATES PATENT OFFICE.

MARK BENNITT, OF SAN FRANCISCO, CALIFORNIA.

FLUID PUMP.

Application filed November 6, 1922. Serial No. 599,436.

My invention relates to improvements in rotating pumps. The objects of my invention are to provide: first, a pump unit having a wide range of adaptability so that the 5 number of units may be adapted to the duty required; second, a pump so constructed as to be run at various speeds and delivering various quantities; third, an efficient pump, simple in construction and economical in 10 upkeep; fourth, a low-speed pump, the units being so spaced as to make a series of short lifts, making high speed unnecessary; fifth, a pump than can be taken out and replaced without disturbing the casing in which it is 15 installed; sixth, a pump whose bearings are protected from the entry of sand or other grit and therefore having a long life. I attain these objects in the manner shown in the accompanying drawings and hereinafter described.

My invention is designed primarily for lifting or propelling water but is adapted to handling heavier or lighter fluids. My pump unit is adapted to numerous modifications 25 of the installation, to be used in such places as mines, quarries, factories, ships, railroad yards, tanneries, refineries, dredges, placer mines, drainage and irrigation works, dry-docks and wells of all depths.

My pump for deep wells is designed to be 30 installed in units or stages in the standard types and sizes of well casings, making a succession of comparatively low lifts by reason of spacing the units at approximately 35 equidistant intervals on the line of shafting. I design to have the bottom unit submerged, making priming unnecessary, although the pump has the suction equivalent of other rotating pumps of the centrifugal or turbine 40 class. The units of any given size are duplicates and when more than one unit is required they are installed on the same line of shafting. Each unit is a complete pump in 45 itself, separated from the others by an interval of shafting.

The preferred plan of installation for deep wells is the one indicated by the drawings accompanying this specification, the pump unit fitting the casing but not being attached 50 to it. By this plan the pump casing is installed first and the pump units are lowered to place afterward. This plan permits the convenient removal and replacement of the pump at will without the trouble and expense of taking out the casing.

Each of the six figures of the accompany-

ing drawings shows a vertical section of my pump unit assembled on a short shaft and in place in a casing, the parts indicated by numbers. The corresponding parts in the 60 several figures are indicated by corresponding numbers. Additional numbers are used for additional parts or features in Figs. 3 and 4, and in Figs. 5 and 6. The several figures are presented also to show different 65 types of rotors and their relation to the other parts.

In the drawings, 1 is the tapered rotor; 2—2, the spiral impelling vanes; 3, the adjusting sleeve and bearing protector; 4, the 70 tapered stationary rotor-seat and bearing support; 5—5, the flat partitions which directly support the bearing; 6, the bushing; 7—7, the resilient annular rings or bands around the outside of the rotor-seat and 75 bearing support; 8—8, the band or sheath covering the resilient rings; 9, the shaft; 10—10, the shaft couplings; 11—11, the casing; 12, the bearing; 13, Fig. 3, an extra sleeve telescoping over the adjusting sleeve; 14, in Fig. 4, a variation of the lower end 80 of the sleeve to cover the bushing, thimble or housing, the sleeve being attached to and turning with the shaft, a shoulder in the sleeve forming a thrust bearing on the end 85 of the bushing, thimble or housing; 15, Fig. 5, another variation, showing the bearing protector held in adjustment against a shoulder on the shaft and forming a thrust bearing against the bushing or housing; 16, Fig. 90 6, a variation showing the bushing extending above the housing and forming a thrust bearing against a shoulder on the shaft, the bearing being protected by a telescoping sleeve attached to and turning with the 95 shaft.

Fig. 1, shows the preferred construction of my rotating pump unit; 1 is my tapered rotor with spiral impelling vanes, 2—2, which are open or free on their outer edge 100 and which combine in their action both a centrifugal and propeller force in a diagonal upthrust, the rotor being designed to receive the fluid at its center near the shaft and discharge it upward and from the top of 105 the rotor at its outer edge near the casing. The adjusting or spacing sleeve, 3, is preferably fixed in the top of the bearing, 12, and extends into a counter-bore in the rotor, forming an end or thrust bearing, where 110 the rotor may revolve freely upon it. The sleeve may be in the form of a long bushing.

extending from the lower part of the bearing to the counter-bore in the rotor. The counter-bore is of such depth that the upper end of the sleeve or extended bushing is 5 beyond the reach of moving water, where sand cannot penetrate, thus protecting the bearing from injury from grit. The rotor-seat and bearing support, 4, is held in adjustment by a collar on the shaft below the bearing or by the shaft coupling serving as 10 such collar. In the drawing the shaft coupling is shown supporting the bearing.

In Figs. 1, 2, and 3, and Figs. 5 and 6, the tapered rotor, 1, with spiral impelling vanes, 2—2, is shown as the male element in the correspondingly tapered, rotor-seat, 4, as the female element, with the adjusting sleeve and bearing protector, 3, in position between them. The adjusting sleeve, in its several 15 variations, permits the rotor to operate close enough to the rotor-seat, without contact with same, to prevent an appreciable back-flow of fluid and consequent loss of efficiency in the pump. The flat partitions between the outer wall of the bearing support 20 and the central bearing form tubular channels for the passage of the fluid and also serve to stop the swirling of the fluid as it approaches the inlet of the rotor in the neck of the rotor-seat and bearing support, 25 thus enabling the spiral vanes to pick it up effectively. The bushing, 6, is of the oilless type. The pump unit is held central in the 30 casing by means of resilient, annular rings, 35 or bands, 7—7, around the exterior circumference of the rotor seat and bearing support. The resilient rings are preferably protected by a metallic band or sheath, lapped at the ends so as to adjust itself to any 40 inaccuracies in the casing as the pump unit is lowered to place. This band or sheath, at top and bottom, is conveniently secured in place by being folded inward over parts 45 of the rotor-seat and bearing support. The resilient rings and protecting sheath, pressing against the casing wall, also serve to prevent the back-flow of fluid around the pump unit.

Fig. 2, shows my pump unit with a 50 tapered rotor having the spiral impelling vanes enclosed by a shell, but otherwise as previously described.

Fig. 3, shows my pump unit with tapered rotor having the spiral impelling vanes enclosed by a shell and discharging at the sides instead of at the top of the rotor. In the same drawing, Fig. 3, an extra sleeve or thimble is shown fixed in the counter-bore of the rotor and telescoping over the adjusting sleeve, this variation of construction being designed for use in dredge work, placer mines, etc., where the water is heavily charged with sand, this sleeve or thimble providing an extra protection to the bearing 65 against the entry of grit.

Fig. 4, shows a fourth type of rotor, in which the spiral impelling vanes have a more pronounced centrifugal thrust near the center of the rotor, curving to an upward, propeller thrust at the rim of the rotor. 70 The sleeve, 3—14, is fixed to the shaft and at its lower end, 14, is enlarged to telescope over an extension of the bushing, thimble or housing, the sleeve having an inside shoulder to form a thrust bearing upon the part over 75 which it telescopes, the object being the same as in the previously described construction, namely, to protect the bearing against the entry of sand or other grit and to hold the rotor and the rotor-seat and bearing support 80 in adjustment with reference to each other.

Another variation of construction is shown at 15, Fig. 5, which provides a shoulder on the shaft, against which the bearing cover is fixed, the cover telescoping over an 85 extension of the bushing, thimble or housing and also serving to exclude the sand and other grit and to hold the rotor and rotor-seat and bearing support in adjustment. Still another variation is shown at 16, Fig. 90 6, a long bushing extending above the housing and forming a thrust bearing against a shoulder on the shaft, being covered by a telescoping sleeve attached to and turning with the shaft, the construction serving the 95 same purpose, that of excluding grit, as the variations previously described.

I claim:—

1. In a rotary pump unit, the combination of a shaft, a tapered rotor mounted thereon 100 having spiral impeller blades, a rotor-seat for said rotor loosely mounted on said shaft and inwardly tapered to correspond to the tapered rotor and a collar on said shaft to support said rotor-seat.

2. In a rotary pump unit, the combination of a shaft, a tapered rotor mounted thereon having spiral impeller blades, a rotor-seat for said rotor loosely mounted on said shaft and inwardly tapered to correspond to the 110 tapered rotor, an adjusting sleeve between said rotor and said rotor-seat, and a collar on said shaft to support said rotor-seat.

3. In a rotary pump unit, the combination of a shaft, a tapered rotor mounted thereon 115 having spiral impeller blades and a hub having a recess surrounding said shaft, a rotor-seat for said rotor loosely mounted on said shaft and inwardly tapered to correspond to the tapered rotor, an adjusting sleeve between 120 said rotor and said rotor-seat and extending into said recess, and a collar on said shaft to support said rotor-seat.

4. In a rotary pump unit, the combination of a shaft, a tapered rotor mounted thereon 125 having spiral impeller blades, a rotor-seat for said rotor loosely mounted on said shaft, and inwardly tapered to correspond to the tapered rotor, an adjusting sleeve between said rotor and said rotor-seat, a second sleeve 130

fixed in a recess surrounding said shaft in said rotor and telescoping over said adjusting sleeve, and a collar on said shaft to support said rotor-seat.

5. In a rotary pump unit, the combination of a shaft, a rotor mounted thereon having spiral impeller blades and a hub having a recess surrounding said shaft, a bearing for said shaft, a sleeve surrounding said shaft and fixed in a recess in said bearing and extending loosely into said recess in said rotor-hub.

10. In a rotary pump unit, the combination of a shaft, a rotor mounted thereon, a bearing for said shaft, a sleeve surrounding said shaft and fixed in a recess in said bearing and extending into a recess in said rotor, a second sleeve fixed in a recess in the said rotor and telescoping over the first sleeve.

15. In a rotary pump unit, the combination

of a shaft, a rotor mounted thereon having spiral impeller blades, a seat for said rotor loosely mounted on said shaft, a collar on said shaft to support said rotor-seat, a casing surrounding said pump unit and a 25 resilient band or bands on the periphery of said rotor-seat between said rotor-seat and said casing.

8. In a rotary pump unit, the combination of a shaft, a rotor mounted thereon having spiral impeller blades, a seat for said rotor loosely mounted on said shaft, a collar on said shaft to support said rotor-seat, a casing surrounding said pump unit, a resilient band or bands on the periphery of said 30 35 rotor-seat, and a sheath lapped so as to be self-adjusting to the casing and between the said resilient bands and said casing.

MARK BENNITT.
